UNITED STATES PATENT OFFICE.

HARRY MARKHAM, OF SAN RAFAEL, CALIFORNIA, ASSIGNOR OF ONE-HALF
TO WILBUR I. THAYER, OF SAME PLACE.

LETTER-OPENER.

SPECIFICATION forming part of Letters Patent No. 635,495, dated October 24, 1899.

Application filed February 23, 1899. Serial No. 706,509. (No model.)

To all whom it may concern:

Be it known that I, HARRY MARKHAM, a citizen of England, residing at San Rafael, county of Marin, State of California, have invented an Improvement in Letter-Openers, and I hereby declare the following to be a full, clear, and exact description of the same.

My invention relates to a device which is especially designed for the rapid and convenient opening of letters.

It consists, essentially, of a base having a knife adjustably fixed thereto with a beveled cutting edge presented downwardly, a spring-guard fixed with relation to the end of the knife, and a channel formed in the base at a point behind the forward part of the cutting edge.

It also comprises details of construction which will be more fully explained by reference to the accompanying drawings, in which—

Figure 1 is a side elevation, partly in section, of the opener. Fig. 2 is a top view of the same.

A is a base of any suitable length and width and provided with a means by which it can be permanently fixed. This base has a vertical slot H or channel made in it near one end of sufficient width to receive the thickness of the rear portion of the cutting-blade B, the front portion of which projects above the surface of the base, as shown. The rear portion of the blade is made of considerable depth, so as to be firmly braced in the slot or channel, and it has a vertical channel b cut out extending from the bottom upward. Through this vertical channel and through the sides of the base passes a screw D, which when loosened allows the blade to be lifted out of its place. When the blade has been set at the proper angle, the screw is tightened and the blade is locked in place. From the front of this deep rear portion the blade tapers to a rounded front end, the upper edge being essentially straight and parallel with the top of the base and the lower edge being inclined or beveled, so that the blade is narrower at the front than the rear. This lower edge is sharpened, and at a point a short distance from the front it approaches closely to the

surface of the base. At this point a depression a is made in the base, so that the rear cutting portion of the blade stands above this depression and entirely clear of the base, the only part that approaches the base being that portion of the edge which is contiguous to the front of the depression. This allows the edge which is to be cut to be drawn along beneath the cutting edge of the knife, and passing between it and the base a clean cut is made, and by reason of the depressed chamber or excavation in the base the article to be cut will be drawn through this depression and will not clog or become choked, as will be liable to occur if the cutting edge terminate at the surface of the base without the rearwardly-extending depression.

In order to properly guide the letter or folded paper to be cut, I have shown a curved spring E, having one end fixed to a vertical post or screw F, and at a short distance in front of this post the spring rests against the pin G. The front end beyond the pin is free to bend outwardly and admit any desired thickness of envelop or other fold which is to be cut.

The operation will be as follows: The front end of the knife being rounded and sharpened the envelop is pressed against the guide-spring, so that the blade enters the open space at the end of the flap of the envelop, and by drawing the envelop rearwardly, guided against the spring, it will be cleanly cut, and passing over the depression made in the base it will not choke or clog the knife; but any length of envelop or folded paper can be drawn along with the certainty of making a clean opening cut. In this manner envelops may be opened with great speed and absolute accuracy.

Having thus described my invention, what I claim as new, and desire to secure by Letters Patent, is—

1. A device for opening envelops consisting of a base and an inverted blade fixed to the base having the cutting edge presented downwardly, said blade tapering to a rounded point and an elastic guide adjacent to the point of the cutter.

2. An envelop-opening device consisting of

a base, a tapering blade having its cutting edge presented downwardly and forming an angle with the base, a depressed chamber formed in the base beneath the rear cutting edge of the knife and a guide adjacent to the front end, substantially as described.

3. An envelop-opening device consisting of a base having a depressed chamber near the rear, a cutting-blade having the edge presented downwardly and diverging upwardly from the front edge of the depression of the base, a channel in the base in which the rear end of the blade is fitted and an adjusting device whereby the blade is set and locked with relation to the base.

4. An envelop-opening device consisting of a base having a depression formed in the surface, a cutter having a rear portion made wide and fitting a vertical slot or channel made in line with the central portion of the depression, a slot formed in the lower side of said

rear portion, a screw passing transversely through the base, the shank of the screw fitting the slot in the lower part of the blade and adapted to adjust and lock it in place, a 25 tapering extension of this rear portion having the cutting edge presented downwardly, extending through the center of the depressed chamber in close proximity with its front edge and rising therefrom above the surface of the 30 base and terminating in a rounded sharpened point whereby the fold to be cut can be passed beneath the cutting edge, and a curved elastic spring standing approximately parallel with the front end of the cutting-blade. 35

In witness whereof I have hereunto set my hand.

HARRY MARKHAM.
